UNITED STATES PATENT OFFICE.

OLIVER N. MORIN, OF HOLYOKE, MASSACHUSETTS, ASSIGNOR OF TWO-THIRDS TO THOMAS F. KILBRIDE AND ARTHUR B. THORPE, OF HOLYOKE, MASSACHUSETTS.

BOILER-FURNACE.

SPECIFICATION forming part of Letters Patent No. 747,207, dated December 15, 1903.

Application filed November 10, 1902. Serial No. 130,691. (No model.)

To all whom it may concern:

Be it known that I, OLIVER N. MORIN, a citizen of the United States of America, and a resident of Holyoke, in the county of Hampden and State of Massachusetts, have invented certain new and useful Improvements in Boiler-Furnaces, of which the following is a full, clear, and exact description.

This invention relates to improvements in boiler-furnaces, and has for its object the provision of means whereby the walls of the furnace-chamber will not become obstructed by accumulations resulting from the intense heat which causes clinkers to adhere to the side walls of the fire-chamber. In order to prevent the formation of clinkers on the side walls of the fire-chamber, I provide pipes through which water may circulate, these pipes being located and embedded within the wall of the fire-chamber and connected with the boiler. I furthermore provide suitable regulating-cocks in conjunction with the circulation-pipes, all substantially as will hereinafter fully appear, and be set forth in the claims.

In the accompanying drawings a manner of carrying out this invention is illustrated.

Figure 1 is a front elevation of the furnace for the boiler, partially in section for more clearly showing the novel parts and the arrangement thereof. Fig. 2 is a longitudinal sectional view through the apparatus. Fig. 3 represents a front view of the boiler and illustrates a hot-water system operated directly from the circulation-pipes above referred to.

In the drawings, 10 represents the fire-chamber of the furnace for the boiler 12, 13 indicating the bridge-wall. I build in any suitable manner along or within the side walls 14 of the furnace feed-pipes 15 15, having at their front ends couplings 16 16, with which are connected upright pipe extensions 17 17, these extensions 17 being united by the couplings 18 with the horizontal pipe 19, which has by the branch 20 a connection with the lower portion of the boiler to receive from the latter a supply of water for circulation through the system of piping of which the pipes pointed out are a part. The said pipes

15 15, extending along within the thickness of the side walls of the furnace, have at their rear ends, which are located within the body of the bridge-wall 13, connections 15^a with the pipes 22, which traverse along the front 55 of the bridge-wall one above the other and have connections with the upper and lower longitudinal pipes 23 23, which are built into or embedded in the side walls of the furnace-chamber. At their forward ends these pairs 6c of pipes are respectively connected with the vertical pipes 24, which are joined by a cross-pipe 25, from which the branch 26 enters the boiler at an upper portion thereof.

It will be understood that the water from 65 the boiler passing from the lower portion thereof into the feed-pipes 15 15 will thereafter be forced or pass through the pipe-sections 22 22 and 23 23 at the forward face of the bridge-wall and in the side walls of the 70 fire-chamber, resulting in keeping the furnace-walls at a materially lower temperature than would be the case in the absence of these pipes, and the water thus enters the boiler at an upper portion thereof in a highly-heated 75 condition.

Cocks 27 are provided between the supply-pipes 15 of the boiler and the feed-pipe 20, these being advantageously comprised in the couplings at 18, and cocks or valves 28 provided in the return-pipes 24. Furthermore, blow-off cocks 30 and 32 are provided at the bottom of the pipes 17 and 24, below the connections therewith of the longitudinal pipes 23 and at the junction of the feed-pipes 15 85 with the branches 17, which connect them with the boiler, respectively.

Originally the blow-off cocks are shut and the cocks or valves 27 and 28 left open; but by leaving open the valves 27, shutting the 90 valves 28, and opening the blow-off cocks 30 the circulation-pipes may be cleared by blowing water therethrough from the boiler, and out through the said blow-off cocks 30, or by closing the valves 27, opening the valves 95 28, and opening the blow-off cocks 32 the system may be cleared by blowing steam therethrough, which will escape at the said blow-off cocks 32.

From the above description it will be un- 100

derstood that the pipes 24 constitute portions of a pipe system which is located outside of the boiler and which connects the water-space of the latter with the steam-space. 5 Hence it will be seen that the water-level in the pipes 24 will be substantially uniform with that inside the boiler. In view of this fact my invention comprises a hot-water system in connection with the circulation system above described, this hot-water system being applicable in supplying hot water to various places in the building, as is, for instance, shown in Fig. 3. Here a pipe 40 is illustrated in direct connection with the return-pipe 24, but at a point below the water-level in the boiler and preferably below the valve 28, so that even if the latter should be closed the pipe 40 will always be full of water. This pipe 40 may have any suitable number 10 of branches 41, leading to different floors or rooms, when hot water may be drawn from faucets 42 into sinks, tubs, or similar appliances 43, as will be readily understood.

Fresh water may be introduced into the 25 boiler through a main supply-pipe 44, having a gate or similar valve 45 and connected with the pipe 19, as shown in Fig. 3, the valve 45 permitting the water to be shut off when the supply in the boiler is sufficient 30 or when the latter is to be blown out.

A valve 46 is provided in the pipe 19 between the pipe 20 and the main supply 44, so that when the gate 45 is open the direct passage of water into the boiler through the pipe 20 35 may be interrupted, and the fresh water may therefore be conducted through the pipe 17 and thence through the circulating-pipes 15, 22, and 23, in this manner efficiently cooling the walls of the fire-box and at the same time 40 itself becoming heated. It is of course evident that the left side of the boiler may be similarly supplied with a supply-pipe, as the right, or that the valve 46 may be disposed in the pipe connection 20, in which 45 case the circulating-pipes on both sides of the fire-box would receive a fresh water-supply simultaneously.

Having thus described my invention, what I claim, and desire to secure by Letters Patent, is—

1. The combination with a boiler and the boiler-furnace, of feed-pipes having connection with the boiler and extending along, and embedded within, the side walls of the furnace, and extended transversely of the bridge-wall, one or more pipes located in the inner side of the bridge-wall, with which said feed-pipes are connected, and pipes connected with the bridge-wall pipes, embedded within, and 55 extended along the inner sides of the furnace-chamber and having return connections with the boiler, substantially as and for the purpose set forth.

2. The combination with the boiler and the 60 boiler-furnace, of pipes connected with the boiler, having extensions and locations along, and embedded within, the inner walls of the

furnace-chamber, and having return connections also embedded within the furnace side walls, and pipe extensions connecting them 70 with the boiler, a shut-off valve located near one terminal of the circulating system of piping and a blow-off cock located in such system inside of the shut-off valve, for the purpose set forth.

3. The combination with the boiler and its furnace, of the feed-pipes 15, 15 extending longitudinally within the side walls of the furnace, and a horizontal cross-pipe 19 having a connection with a lower portion of the 80 boiler and pipe connections between said cross-pipe and said feed-pipes 15, 15, the pipe-sections 22, 22 transversely extending partially across and within the front side of the bridge-wall and connected to the said 85 feed-pipes 15 and the pipe-sections 23, 23, connected to the pipe-sections 22, 22, extending longitudinally along and within the side walls of the furnace, upright pipe-sections 24, 24 with which said sections 23 are connected at the front of the furnace, and the cross-pipe 25 uniting the upper ends of said upright pipes, and having a branch connecting it with an upper portion of the boiler substantially as described.

4. In combination the boiler and its furnace thereunder, the longitudinal feed-pipe sections 15, 15 horizontal branch 19 boiler connection 20 pipe connections 17, 17, between said branch 19 and said feed-pipes, 100 shut-off valves between the feed-pipes 15 and the boiler connection, and blow-off cocks between the shut-off valve and the feed-pipes, the pipe-sections 22, 22, in the bridge-wall connected with the feed-pipes, the transverse 105 pipe-sections 23, 23 in and along the side walls connected to the pipe-sections, the upright pipe-sections 24, 24, with which the forward ends of the pipe-sections are connected, having connections at their upper ends with 110 an upper part of the boiler, and being provided with shut-off valves, and the blow-off cocks between forward portions of the longitudinal pipe-sections and said last-named 115 shut-off valves all substantially as described and shown.

5. The combination with a boiler and the boiler-furnace, of a pipe 44 leading from a source of supply and having continuation 19 connected with a lower portion of the boiler 120 and having a valve 46 permitting, or preventing the water from, directly entering the lower portion of the boiler and having the valve 45 remote, and in the direction of the source of water-supply, from the valve 46, a 125 pipe-section connected in the conduit 19 between said two valves having a course rearwardly along, and a course 23, returning forwardly along, and embedded within the side walls of the fire-chamber to the outside of 130 the furnace-front, for the purpose described, a vertically-extending pipe-section 24, with which said returning-conduit is connected, extending to connection with an upper por-

tion of the boiler, a pipe 40 for the heated water connecting into the pipe-section 24 between the connection of return-pipe 23 therewith and the upper connection of said pipe 24 with the boiler, and a valve 28 in the pipe 24 above the connection therewith of said pipe 40.

Signed by me at Springfield, Massachusetts, in presence of two subscribing witnesses.
